REVOLVING CHAIR

Calvin S. Greenwood, Gardner, Mass.

Application August 10, 1942, Serial No. 454,286

2 Claims. (Cl. 155—95)

The present invention relates to revolving chairs, and particularly to the construction of chair bases used in connection with revolving chair seats, stools and the like.

The principal object of the invention is to provide a chair of this character having an all wood construction, including suitable bearings for rotatably supporting the standard or shank of the chair seat, as well as for supporting the weight of the seat itself. By thus utilizing an all wood construction, the employment of metal parts, such as have heretofore been incorporated in revolving chairs, is entirely eliminated, thus rendering the chair manufacturer more or less independent of existing shortages in metals.

A further object of the invention is to provide in an all wood chair construction of the above indicated character, convenient means for adjusting the height of the seat, without the use of any tools or adjustable metal parts, such as have heretofore been employed.

The above and other advantageous features of the invention will hereinafter more fully appear from the following description, considered in connection with the accompanying drawing, in which:

Fig. 1 is a view in side elevation of a revolving chair embodying the present invention.

Fig. 2 is a perspective view of the chair shown in Fig. 1, so tilted as to show the relation between the base construction and the seat.

Fig. 3 is a fragmentary sectional view, on an enlarged scale, through the chair base.

Fig. 4 is a perspective view, illustrating the arrangement of the bearing parts on the seat shank.

Fig. 5 is a sectional view similar to Fig. 3, illustrating the improved means for adjusting the height of the chair seat.

Fig. 6 is a horizontal sectional view along the line 6—6 of Fig. 5, looking in the direction of the arrows.

Referring first to Figs. 1 and 2, the invention is shown as being embodied in a chair base assembly indicated by the reference character 1, with the chair base being supported above the floor level by legs 2. A seat 3 is revolvably mounted on the base 1, and provides a suitable back 4, which can be omitted if it is desired to employ the present construction in a stool.

The under side of the seat 3 carries a shank plate 5, and as best shown in Fig. 3, this plate provides a centrally located opening 6, within which is received the upper end of a shank 7 extending downwardly through the base 1. The

shank 7 is of wood, and its upper end is anchored firmly in the plate opening 6 by means of a wedge 8 driven into a slot 9 extending axially of the shank, so as to expand the shank within the plate opening. After the shank 7 has been thus secured within the plate 5, the latter is fastened to the under side of the seat 3 by any suitable means, as by an adhesive or fastening devices 10.

As best shown in Fig. 3, the base construction 1 consists of an assembly formed by the upper end portions 11 of the legs 2, which portions 11 are secured to a solid cylindrical hub member 12 providing a central passage 13, through which the shank 7 freely extends. Thus, the legs 2 and hub member 12 form a self supporting assembly for the base, and the present invention is particularly concerned with the provision of means for rotatably supporting both the shank 7 and the seat 3 on the base structure, without the use of any metal bearing.

To this end, the base provides a top bearing plate 14 rigidly secured to the assembled leg portions 11, which radiate from the hub structure. The plate 14 provides an opening 15 of greater diameter than the shank 7, and this opening is provided with an enlarged seat 16 for receiving a sleeve bearing 17, the internal diameter of which is such as to provide a running fit with the shank 7. The sleeve bearing 17 is formed of wood impregnated with a suitable lubricant.

The upper surface of the plate 14 is countersunk around the seat 16 to provide a wide annular seat 18 lying in a horizontal plane, and concentric with the seat 16, which receives the sleeve bearing 17. This seat 18 freely receives a flat bearing disk 19 of annular form which, as best shown in Fig. 4, provides a central opening 20 loosely surrounding the shank 7.

It will be noted from Fig. 3 that the thickness of the bearing disk 19 is somewhat greater than the vertical depth of the seat 18, so that the upper surface of the disk 19 directly supports the lower surface of the shank plate 5. That is to say, when the shank 7 has been inserted in the hub and centered therein by the sleeve bearing 17, the weight of the seat 3 is largely borne by the relatively large area of the bearing disk 19. The disk 19 is composed of wood impregnated with a lubricant, such as oil or graphite, so that the seat will always turn freely on the base. In fact, it has been found that after the chair has been in use, the lubricant with which the disk 19 is impregnated works into the fibres of the lower face of the shank plate 5, to such an extent that the seat 3 turns with great freedom.

The lower end of the hub structure is provided with a bottom bearing plate 21, suitably secured to the leg portions 11, so as to further brace the hub structure. The plate 21 is formed with an opening 22 of slightly greater diameter than the shank 7, above which opening 22 the hub member 12 is provided with an enlarged seat 23 for receiving a cylindrical bearing sleeve 24 held in position by the plate 21. The inside surface of this bearing sleeve 24 makes a running fit with the shank, and the sleeve 24 is also composed of wood impregnated with a lubricant.

From the foregoing, it is apparent that the wooden shank 7 carried by the plate 5 is supported for turning about a vertical axis, in such manner that side play is prevented. Due to the lubricant which impregnates the sleeve bearings 17 and 24, the fibres of the shank 7 absorb this lubricant after the chair has been in use, so that the shank will turn freely, and can be readily withdrawn from the base. Wear between the shank 7 and the sleeve bearings 17 and 24 is reduced to a minimum, due to the fact that the weight of the seat and its occupant is borne by the bearing disk 19 which, as previously pointed out, provides a bearing surface of considerable area, as compared to the cross sectional area of the shank 7.

As previously pointed out, the invention also contemplates an all wood chair base construction, which will permit the chair seat 3 to be adjusted for different heights, without disturbing the arrangement and functioning of the varying elements previously described. Such a modified construction is shown in Fig. 5, wherein parts having the same functions as in Fig. 1 are designated by the same reference characters.

In the modified structure, the sleeve bearing 17 and the flat bearing disk 19 are carried by an intermediate bearing plate 25, from the lower surface of which extends a set of diametrically opposed spacing pins 26 extending downwardly in the direction of a top plate 27 forming part of the hub structure. As best shown in Fig. 6, the hub plate 27 is provided with a series of openings 28, 29 and 30 of different depths, such openings being arranged concentrically about the axis of the shank 7 at the same radial distance therefrom as the pins 26. It will be noted that the top surface of the plate 27 provides equal spaces between the members of each series of openings, and that the openings 28, 29 and 30 of the same depth are diametrically opposed with respect to

the shank axis. Therefore, all four pins 26 may be received in any given series of openings 28, 29 or 30, or may rest on the top of the plate 27 between these openings.

With the above described arrangement of spacing pins 26 and openings 28, 29 and 30, it is possible to adjust the distance between opposed faces of the plates 25 and 27, and so determine the height of the seat 3 above the floor. For example, with the pins 26 received in the openings 30, which extend through the plate 27, the plate 25 is resting on the plate 27, and the seat 3 is at its lowest level. However, with the pins 26 received in the openings 29 of intermediate depth, as shown in Fig. 5, the seat 3 will be supported at a level intermediate between the levels obtained with the pins received in the openings 28 and 30, respectively.

I claim:

1. A revolving chair construction comprising in combination a seat provided with a downwardly extending shank, a base provided with a central opening for receiving said shank and of greater diameter than said shank, a top plate mounted on said base provided with a central opening for receiving a sleeve bearing fitting a portion of said shank where it enters said base opening, with said top plate having its upper face provided with a countersunk recess surrounding said sleeve bearing, and an annular bearing disc received in said recess for supporting said seat, with said shank being composed of wood and said sleeve bearing and disc being composed of wood impregnated with a lubricant.

2. A revolving chair construction comprising in combination a seat provided with a downwardly extending shank, a base provided with an opening for receiving said shank and of greater diameter than said shank, with the upper portion of said base provided with a plurality of series of openings of different depths arranged in spaced relation around the shank axis, a plate provided with an opening in which is received a sleeve bearing surrounding a portion of said shank, with the central portion of the upper face of said plate being countersunk to receive an annular bearing disc for supporting said seat, and with the lower face of said plate provided with a series of downwardly projecting pins spaced around the shank axis for reception in different series of said openings to support said bearing plate and seat at different levels with respect to said base.

CALVIN S. GREENWOOD.
